SHORE JACK

Lawrence S. Holmboe, Sr., Oklahoma City, Okla.

Application January 18, 1954, Serial No. 404,426

2 Claims. (Cl. 254—120)

The present invention relates to an improvement in shore jacks, and more particularly to shore jacks for use in shoring, bracing, jacking and scaffolding, as used ordinarily in general construction work. It can be used as well in connection with buildings and reinforced concrete structures of all kinds, in connection with mines, in connection with braces for sewers and other trenches, in connection with scaffolds and hoist towers, and in connection with like uses where such a member is desired.

The present invention is an improvement upon my device as shown in my Patent No. 2,178,792, issued November 7, 1939, for a Shore Jack. The primary objection to the use of this shore jack is that when considerable pressure is exerted upon the lower end of a shore member, the cam edge of the lever tends to damage and ultimately split the end portion of the shore. It is to overcome this difficulty that the present improvement was designed.

The primary object is to provide a jacking device of the character described which will not materially damage the shoring and which may be used by one hand of the operator, leaving the other hand free to handle the shoring and the like.

Another object is to provide a jacking device with an attaching shoring protector that is always in place and ready for its intended use.

Another object is to provide an alternate embodiment of a shore protector for a jacket device that may be placed in position for use when needed to protect the shore and that may be comparatively cheaply manufactured and added to shoring jacks already in use.

Other objects will be apparent from the following description when taken in conjunction with the accompanying two sheets of drawings, wherein:

Figure 1 is a perspective view of the improvement per se;

Figure 2 is an elevational view of the device on a shoring jack in position on a shore as shown in dotted lines, and showing in dotted lines the lifting action of the jack and the device;

Figure 3 is a plan view of the device on a shoring jack;

Figure 4 is a right side view of the device as seen in Fig. 2;

Figure 5 is a perspective view of an alternate embodiment of the device per se;

Figure 6 is an elevational view of the alternate embodiment of the device on a shoring jack in position on a shore as shown in dotted lines, and showing in dotted lines the lifting action of the jack and the alternate embodiment of the device;

Figure 7 is a plan view of an alternate embodiment of the device on a shoring jack; and

Figure 8 is a right side view of the alternate embodiment of the device as seen in Fig. 6.

Like characters of reference designate like parts in those figures of the drawings in which they occur.

2

In the drawings:

The reference numeral 1 designates the lower one of a pair of shore members, and numeral 2 designates the lower end portion of the upper one, both fitting together and adapted to slide longitudinally with relation to each other while being adjusted, and being held securely thereafter by shore clamps (not shown).

The jacking device consists substantially of a one piece U-shaped pivoting collar designated, as a whole, by the numeral 5, having a body 6 with perpendicularly outstanding arms 7 and 8. The arms 7 and 8 are provided with pivot pins 9 and 10 for holding in connection with cotter keys gripping plates 11 and 12, respectively. On one of the arms, preferably arm 7, is an upstanding boss 13, having a perpendicular extending pivot pin 14. Pivotally attached on said pin 14, by a cotter key 15, is a lever 16 having an eccentric or cam head 17, the outer edge of said cam 17 at right angle to the lever 16 presents a transversely flat surface, as best shown at 18, Figs. 4 and 8.

The above description of the jacket device is fully covered by my patent mentioned hereinabove, and is presented here only to show a workable device in connection with the present invention.

Reference numeral 20 indicates, as a whole, a pressure plate having a substantially square body 21 and an upwardly arcuate upper surface 22. However, the top surface 22 of plate 20, if desired, may be made flat in configuration. To the lower surface of the body 21 is rigidly attached a spaced parallel pair of depending strip metal legs 23 and 24, positioned edgewise longitudinally with the arcuate surface 22. The spacing of the legs 23 and 24 is such as to freely receive the cam portion 17 of the lever 16. The legs 23 and 24 are through pierced by a pair of co-operating longitudinally extending slots 25 and 26, respectively. Each slot 25 and 26 has a width sufficient to freely receive and pivot on the pin 14, and a length great enough to permit the cam head 17 to raise the body 21 to the uppermost part of the cam arc. The plate 20 is placed upon the cam head 17 with the legs 23 and 24 straddling the cam head and the pivot pin 14 through the co-operating slots 25 and 26, and is held in place on the pin 14 by the cotter pin 15, Figs. 2 and 4. The body 21 is held in substantially a horizontal position by an upstanding lug 27 upon the uppermost part of the boss 13, Fig. 4. The lug 27 is substantially rectangular in general configuration, lying longitudinally parallel with and disposed vertically above the pin 14, and having a width somewhat narrower than the slot 26, as shown in dotted lines, Fig. 3. The lug 27 extends longitudinally with the pin 14, within the slot 26, past the free edge of the arm 7, a distance substantially equal to the thickness of the leg 24. Thus the plate 20 may pivot or rock upon the pin 14 only to the extent that the sides of the lug 27 will allow the movement of the slot 26 thereupon.

Operation

The jacking device 5 is placed upon a shore 1, with the lever end 7 under the upper shore, as shown in Fig. 2. In this position the arcuate surface 22, of the pressure plate 20, is adjacent the lower end of the upper shore 2. The lever 16 is raised, as shown by the dotted lines in Fig. 2, and the transversely flat surface 18, of the cam head 17, contacts the lower surface of the pressure plate body 21, forcing it upwardly against the lower end of the shore 2. The purpose of the arcuate surface 22 is to insure a substantially transverse flat contact with the lower end of the shore 2, to prevent damage thereto. It is possible to lift approximately three thousand pounds with the jacking device 5 and therefore it is believed quite evident that some means such as the present improvement

should be provided to protect the shore end while under such pressure.

An alternate embodiment of the device is shown in Fig. 5, and is indicated, as a whole, by the reference numeral 30. This alternate embodiment is a substantially flat rectangular plate, having one end of a comparatively short handle 31 rigidly attached transversely across the left end of the plate, as seen in Fig. 5, and extending outwardly and laterally from the plate 32. The plate 32 is of a length sufficient to substantially extend across the bottom end of the shore 2, and a width great enough to extend from the back, or right hand side, as seen in Fig. 6 of the shore 2, along the bottom of the shore toward the shore 1, to provide a bearing surface for the flat portion 18 of the cam head 17. A comparatively short rectangular bar 33 is rigidly attached, as by welding, at a selected point between the ends of the longitudinal side of the plate 32 adjacent the free end of the handle 31 perpendicular to the plate 32, and extending slightly upwardly above its upper surface. A similar bar 34 is similarly attached to the end of the plate 32 adjacent the rigid end of the handle 31. The alternate plate 30 is attached to the jacking device 5 by a suitable length of chain 35, having one end rigidly attached, as by welding, to the end of the plate 32 adjacent the rigid end of the handle and the opposite end attached to the eye of the cotter pin 15.

The purpose of the alternate embodiment 30 is identical with the purpose of pressure plate 20, Fig. 1, and the operation is similar except that the plate 30 must be positioned upon the cam surface 18, contacting the lower surface of the upper shore 2, by the operator. The operator grasps the handle 31 and places the upper surface of the plate 32 adjacent the lower surface of the shore 2 with the bars 33 and 34 contacting the back or right side and near side of the shore 2, as seen in Fig. 6, and as more clearly illustrated in Fig. 8. When the plate 30 has been positioned, the handle 16 may then be raised, lifting the shore 2 the desired amount.

Obviously the invention is susceptible to some change or alteration without defeating its practicability, and I

therefore do not wish to be confined to the preferred embodiment shown in the drawings and described herein, further than I am limited by the scope of the appended claims.

5 I claim:

1. In combination with a shoring jack including, a rigid U-shaped frame adapted to embrace a shore member, substantially flat gripping plates connected co-operatively to the arms of the U frame for gripping opposite sides 10 of the shore member, load-lifting means supported by the U frame, said means including a cam lever pivotally connected to one end of said frame; a flat surfaced rectangular pressure plate, said plate having a rigid handle projecting outwardly in angular relation from one end 15 of the plate; a pair of short upstanding bars rigidly carried by said plate at said one end and at one side edge, respectively, for contacting the sides of a shore and positioning the plate between said cam and the shore; and flexible means connecting said plate to said U frame.
- 20 2. In combination with a shoring jack including, a rigid U-shaped frame adapted to embrace a shore member, substantially flat gripping plates pivotally connected co-operatively to the arms of the U frame for gripping opposite sides of the shore member, load-lifting means supported by the frame adjacent to one of the arms of the U frame tending to tilt the frame and gripping plates; a flat surfaced rectangular pressure plate, said plate having a rigid handle projecting outwardly in angular relation from one end 25 of the plate; a pair of short bars rigidly carried perpendicularly by said plate at said one end at one side edge, respectively, for contacting the sides of a shore and positioning the plate between said load-lifting means and the lower end of a shore; and a chain connecting said plate to said U frame.
